United States Patent Office.

EDWARD BOURNE, OF PITTSBURG, PENNSYLVANIA.

Letters Patent No. 97,866, dated December 14, 1869.

IMPROVEMENT IN RIVETS AND WASHERS.

The Schedule referred to in these Letters Patent and making part of the same

To all whom it may concern:

Be it known that I, EDWARD BOURNE, of Pittsburgh, in the county of Allegheny, and State of Pennsylvania, have invented a new and useful Improvement in Rivets and Washers, used for uniting the thin metallic sheets of steam-heated radiators; and I hereby declare that the following is a full, clear, and exact description of my invention, reference being had to the accompanying drawings, forming part of this specification, and to the letters of reference marked thereon, in which—

Figure 1 represents a longitudinal vertical section of two thin metallic sheets united by my plan.

Figure 2 represents a top view of the same.

Figure 3, an enlarged sectional view of the outside washer.

Figure 4, an enlarged sectional view of large inside washer.

Figure 5, enlarged view of the rivet.

All the parts are lettered, and similar letters denote like parts in the several views.

This invention is designed as an improvement upon that for which Letters Patent were granted to me the 9th day of February, 1869, numbered 86,726. In that case the inside washer was made with only one end of its central hole concave, so that when used in connection with a conical-headed rivet, that portion of the sheet immediately around the head of the rivet, on "closing it down," was drawn into the concavity of the washer.

In this case I have made the central hole in the inside washer B concave at both ends, and use in connection therewith a convex washer, *a*, so that the sheet N, farthest from the head of the rivet C, will be drawn into the concavity of the washer B at that point, in the same manner and to the same extent as the head of the rivet C draws the sheet P into the concave portion of the inside washer B at its end, as described in the hereinbefore-mentioned patent.

This invention is designed for uniting the thin metallic sheets of such steam-heated radiators as are in use for warming houses, halls, and the like; and the great difficulty of making them perfectly steam-tight around both ends of the rivets is, in this case, entirely overcome, owing to the length of bearing each sheet is given in the central washers at its point of contact.

The curving of the sheets inward, at and around each end of the rivets, and the plan of drawing that portion into the concavities of the central washer, not only prevents leakage, but tends to stiffen both sheets and aid them in withstanding the outward pressure of steam.

I claim the combination of the rivet C, washers B and *a*, all constructed as described.

EDWARD BOURNE.
